US00D985718S

(12) **United States Design Patent** (10) **Patent No.:** **US D985,718 S**
(45) **Date of Patent:** **** May 9, 2023**

(54) **ELECTROSTATIC SPRAY PROBE**

(71) Applicant: **Graco Minnesota Inc.**, Minneapolis, MN (US)

(72) Inventors: **Amelia J. Stech**, St. Paul, MN (US); **Elisa J. McCLine**, Elk River, MN (US); **Mark E. Ulrich**, Oak Grove, MN (US); **Mark C. Richter**, River Falls, WI (US)

(73) Assignee: **Graco Minnesota Inc.**, Minneapolis, MN (US)

(**) Term: **15 Years**

(21) Appl. No.: **29/840,873**

(22) Filed: **Jun. 1, 2022**

Related U.S. Application Data

(60) Division of application No. 29/811,033, filed on Oct. 11, 2021, now Pat. No. Des. 956,177, which is a continuation of application No. 29/693,195, filed on May 31, 2019, now Pat. No. Des. 934,383.

CLAIM

The ornamental design for an electrostatic spray probe, as shown and described.

DESCRIPTION

FIG. 1 is a perspective view of an electrostatic spray probe; FIG. 2 is a front elevational view of the electrostatic spray probe;

FIG. 3 is a rear elevational view of the electrostatic spray probe;

FIG. 4 is a right side view of the electrostatic spray probe;

FIG. 5 is a left side view of the electrostatic spray probe; FIG. 6 is a top plan view of the electrostatic spray probe; and,

FIG. 7 is a bottom plan view of the electrostatic spray probe. The broken lines are shown for environmental purposes and form no part of the claimed design.

1 Claim, 7 Drawing Sheets
